UNITED STATES PATENT OFFICE.

AUGUSTUS F. NAGLE, OF BETHLEHEM, PENNSYLVANIA.

PUMP-VALVE AND VALVE-DECK.

1,082,646.

Specification of Letters Patent. Patented Dec. 30, 1913.

Application filed April 5, 1913. Serial No. 759,004.

To all whom it may concern:

Be it known that I, AUGUSTUS F. NAGLE, residing at Bethlehem, in the county of Northampton and State of Pennsylvania, have invented certain new and useful Improvements in Pump-Valves and Valve-Decks, whereof the following is a specification, reference being had to the accompanying drawings.

10 My invention relates to a valve deck for pumps, upon which a number of small valves are mounted. These larger decks are expensive and the adjoining castings a source of weakness to the pump. It is hence 15 desirable to keep the deck as small as can be done without unduly limiting the capacity of the valves.

My invention relates to a method of construction whereby without unduly weakening the valve deck, a greater quantity of water may be caused to travel through the valves mounted thereon, than in previous 20 constructions. This is accomplished by so spacing the apertures of the valve deck, 25 as to afford the maximum total aperture without undue weakening of the deck, and then providing each aperture with a flaring or bell-shaped valve body, standing out from the deck, so that the total ultimate aperture at the valve seat is at least equal to 30 the corresponding aperture of the valve deck, notwithstanding the interposition near the valve seat, of the necessary supporting frame for the valve stud. In this 35 way I have succeeded in greatly increasing the capacity of a valve deck of this character. At the same time each individual valve is visible for examination in contrast with the valves now prevalently used in the 40 well known cage construction, on which the valves are mounted in cages which are mounted on the valve deck. My construction also gives ready access for repairs or renewals, without disturbing any other 45 valve, and without breaking any permanent joints.

In the accompanying drawings, Figure I, represents a circular valve deck as employed in my construction, the valves being removed therefrom. Fig. II, is a section of the same along the line II, II, with the valves *in situ*. Fig. III, is an enlarged elevation of a part of Fig. II.

The valve deck is provided with numerous 55 apertures 2, in staggered relation to each other, and so spaced as not to unduly weaken

the valve deck, as would be the case if the apertures were more closely to each other. In a large deck it is desirable that means for strengthening the deck should be provided in the form of webs 3, 3, on the under side of the deck.

Each aperture 2, is threaded and has screwed into it, a valve body 5, terminating in a circular valve seat 6, furnished near the top thereof with a spider frame 7, which supports centrally the valve stud 8, around which slides the hard rubber valve 9, under compression by the exposed spiral spring 10, which is interposed between a metal washer 11, attached to the upper surface of the valve, and a metal cap 12, fast upon the top of the stud.

It is characteristic of my invention that the valve body 5, which is attached at its lower end to the aperture in the valve deck, flares upwardly toward its seating surface, thereby assuming a "bell-shape". In this way, I am able to interpose the spider-frame, or other supporting means for the valve stud, within the aperture of the valve seat, without restricting its effective orifice, the capacity of the valve remaining the same as that of the aperture in the valve deck, through which the water flows to it. These valve seats are not so closely mounted to each other, but that each one is accessible for separate examination and repair, and it will be noted that all working parts of the valve are left entirely open, there being no casing surrounding the valve or its operating parts.

The valve bodies heretofore used have had straight sides, and their throats obstructed by the ribs supporting the central stud, thereby limiting the capacity of the valve. If, to overcome this, the size of the valve body is increased, the spaces between the threaded holes in the valve deck become so small, as to unduly weaken it. This is clearly shown in Fig. III, where the minimum valve space 13, is accompanied by the maximum strength of metal 14. Were it not for my invention the spaces 13, and 14, would be substantially alike, with the consequences described.

As an expression of the value of my invention, I may state that I can obtain with similar proportions of strengths, the same number of valves on a forty-eight inch deck, with my invention, as would require a fifty-six inch deck in previous constructions. It will be understood that my invention does

not relate to the construction of the valve proper, which may vary.

Having thus described my invention, I claim:

5 The combination of a valve deck provided with a multiplicity of apertures; valve bodies associated with each aperture and projecting from the plane of the valve deck, said valve bodies being provided with valve seats,
10 valves, and valve supporting means outside of the plane of the valve deck, and with

sides which are flared outwardly between the plane of the valve deck and the plane of the valve supporting means.

In testimony whereof I have hereunto 15 signed my name at Philadelphia, Pennsylvania, this third day of April, 1913.

AUGUSTUS F. NAGLE.
